US00D651533S

(12) **United States Design Patent**
Chase et al.

(10) **Patent No.:** US D651,533 S
(45) **Date of Patent:** ** Jan. 3, 2012

(54) **FIXED RATIO METERING SYSTEM**

(75) Inventors: **Daniel J. Chase**, Wadsworth, OH (US);
Thomas R. Fagan, Jr., Tallmadge, OH (US); **Paul Michael Jones**, Austintown, OH (US); **David M. Muckley**, Uniontown, OH (US); **Charles J. Wheeler**, New Philadelphia, OH (US); **Brian L. Allen**, Massillon, OH (US)

(73) Assignee: **Graco Minnesota Inc.**, Minneapolis, MN (US)

(**) Term: **14 Years**

(21) Appl. No.: **29/376,025**

(22) Filed: **Sep. 30, 2010**

(51) **LOC (9) Cl.** 10-04

(52) **U.S. Cl.** **D10/101**; D15/199

(58) **Field of Classification Search** D10/46, D10/101; D15/199; D23/213, 499; 74/675; 137/99, 567; 222/46, 134, 135, 137, 333

See application file for complete search history.
